UNITED STATES PATENT OFFICE

171,671

GOBLET OR SIMILAR ARTICLE

Carl J. Uhrmann, Bellaire, Ohio, assignor to Imperial Glass Corporation, Bellaire, Ohio, a corporation of Ohio

Application February 24, 1953, Serial No. 23,733

Term of patent 14 years

(CL. D36—8)

To all whom it may concern:

Be it known that I, Carl J. Uhrmann, a citizen of the United States, residing at Bellaire, county of Belmont, and State of Ohio, have invented a new, original, and ornamental Design for a Goblet or Similar Article, of which the following is a specification, reference being had to the accompanying drawing, forming a part hereof, in which:

I claim:

The ornamental design for a goblet or similar article, substantially as shown.

CARL J. UHRMANN.
